Troy D. Smedley
Attorney

UNITED STATES PATENT OFFICE.

TROY D. SMEDLEY, OF WATERLOO, IOWA.

SWING.

Application filed July 30, 1927. Serial No. 209,545.

My invention relates to improvements in swings, and the object of my improvement is to provide a swing which also includes the feature of an elongated carrier particularly 5 for children's use, but which may be employed as an amusement for adults.

Another object of my improvements is to so shape the carrier member or device of the swing as to prevent any collisions thereof 10 with the ground or surface below, while rendering the seats thereof more readily accessible to be mounted or for persons to leave the same than other devices of this class.

Another object of my improvements is to 15 construct the carrier member or device of adjustably connected sections, whereby the swing may be adjusted with a longer or shorter length of the carrier, or to permit the latter to have opposite parts of unequal 20 lengths to balance persons seated upon said parts, who may differ in weight.

Another object is to supply means whereby 25 the carrier may be swung by either the persons seated thereupon or by others without, and to include resilient means operative upon the carrier during its actuation in the storing of power.

Another object is to so construct the carrier 30 part of the swing that several persons may be seated on each end part thereof, with provision made also for them as hand and feet supports thereon.

These objects I have accomplished by the 35 means which are hereinafter described and claimed, and which are illustrated in the accompanying drawings, in which Fig. 1 is a view, partly in side elevation and partly in medial longitudinal section, of my invention. Fig. 2 is a top plan of the swing.

40 My invention is not restricted to the precise construction and arrangement of parts herein shown and described, nor to the various details thereof, as the same may be modified or rearranged in various particulars without departing from the spirit and scope of my invention, one practical embodiment of which has been herein illustrated and described without attempting to show all of the various forms and modifications in 45 which my invention might be embodied.

The numeral 2 denotes a pair of tubular standards, spaced transversely, and having their lower ends rigidly stepped as in an

anchoring cross block 1 of concrete embedded in the soil.

55 On the top of each standard 2 may be fixed an inwardly directed elbow 3 to receive a cross tube 4, thus providing a rigid supporting frame for the swinging carrier device therebetween. Upon each end part 60 of the cross tube 4 is rockingly mounted a short strong sleeve 5 having a surrounding flange the lower part 6 of which flange is widened radially and across and apertured to receive the bent over upper terminations 65 of three depending rods 7, the middle one normally vertical and the rods 7 to front and rear thereof diverging therefrom downwardly.

A carrier structure is fixed upon the lower 70 ends of these divergent rods 7 at the sides, the construction of the carrier being of any desired kind without departing from my invention, but one practical embodiment is illustrated which includes the several novel- 75 ties of the invention.

This structure includes transversely spaced pairs of arcuate angle bars 12 at each end of the carrier connected by bolts 15 to the abutting and overlapping ends of a pair 80 of transversely spaced medial angle bars 13, a number of bolt-holes 14 being provided in the latter aligned longitudinally to permit of relative longitudinal adjustments between the bars 12 and 13, so that the whole structure 85 may be varied in its length, or an adjustment made whereby the bars 12 on one end of the structure are retracted inwardly only, so as to render the structure balanced when the persons seated on opposite parts 90 thereof are of different combined weights. The lower end of the middle rods 7 are threaded to enter holes in the top flanges of the angle bars 13 and secured by nuts. The same securing means are provided for the 95 outer and divergent rods 7 to secure them to the outer bars 12. Flat bars 16 may be fastened across the outer ends of the upper faces of the angle bars 12, and these may carry the seat or bench elements 17 which 100 may be of any desired length to seat a number of persons side by side thereon, and cross-ribs 18 may be fixed on the benches to afford a measure for preventing side slip for those seated.

105 A cross-bar 21 is also fixed across each

pair of bars 12 before each seat 17 to serve as foot-rests. On the forward and rear pairs of depending and divergent rods 7 sleeves 8 are adjustably fitted and secured by wing-screws or set screws 11, and projecting from the opposite parts of said sleeves are fixed arms 9 terminally apertured to seat the ends of hand-bars 10, which may be grasped by persons seated on said seats 17. These sleeves 8 may be quickly adjusted in position up or down on said rods 7 to suit the convenience of the seated persons.

Relatively long coiled tension springs 23 are connected at each side between headed pins 24 fixed near the base on the inner face of each standard 2 and eye-bolts 22 secured to the angle-bars or preferably as shown to the cross-bars 21. Pull-ropes 20 may be connected to opposite ends of the swinging structure, whereby persons standing near may start the device in operation swinging.

Persons seated on the device will operate the swinging carrier by body movements as usual, being supported in such movements by the adjustable hand-bars 10. It will be observed that the arcuate swinging bars 12—13 always clear the surface of the ground below, so that there is no interference notwithstanding a wide scope of swinging.

The device as shown, is a strongly braced, relatively light skeleton structure, both in the supports and in the swinging device. Being constructed of stock shapes in most particulars, with little labor cost other than in assembling, the device is relatively inexpensive. The oppositely tensionable springs 23 permit a storage of power which equalizes the action of the swing, and perpetuates the swinging longer when the seated persons desist from efforts.

As this invention may be constructed with different dimensions and modifications within the scope of allowable mechanical equivalents, the device may be provided for use as lawn, playground or play room, or porch swings, also for miniature doll swings, or otherwise employed in any manner as may be found desirable.

Having described my invention, what I claim as new, and desire to secure by Letters Patent, is:

1. In combination, supporting standards, an adjustably connected sectional skeleton arcuate structure swingingly supported thereon and therebetween, said structure being composed of spaced side bars with rigid cross connections, a plurality of seats supported across the outer ends of said structure, and resilient devices between said standards and said structure, and mounted to act oppositely on said structure.

2. In combination, supporting standards, an adjustable elongated sectional skeleton frame structure swingingly supported thereon, said structure being composed of spaced arcuate side bars and each side bar having adjustably connected sections, seats on opposite parts of said structure, and resilient means connected to opposite parts of the structure to exert tensions thereon in either of opposite directions relative to certain directions of movements of the structure.

3. In combination, supporting standards connected rigidly at their tops by a cross member, sleeves rockingly mounted on said cross member, end and medial rods depending divergently from said sleeves, and an elongated sectional longitudinally adjustable skeleton frame structure suspended on the lower ends of said rods, consisting of a medial and end sections adjustably connected together with the medial rods connected medially to and supporting said medial sections whereby said structure with said rods and sleeves provide a rigidly framed device.

4. In combination, supporting standards, an elongated curvate structure consisting of parallel sets of connected sections longitudinally adjustable swingingly supported thereon, and seats on the opposite parts of said structure with means for swinging the structure.

In testimony whereof I affix my signature.

TROY D. SMEDLEY.
